UNITED STATES PATENT OFFICE.

JOSIAH DOW, OF PHILADELPHIA, PENNSYLVANIA.

ROTARY ENGINE.

SPECIFICATION forming part of Letters Patent No. 673,470, dated May 7, 1901.

Application filed May 12, 1900. Serial No. 16,412. (No model.)

To all whom it may concern:

Be it known that I, JOSIAH DOW, a citizen of the United States, and a resident of the city and county of Philadelphia, State of Pennsylvania, have invented certain new and useful 5 Improvements in Rotary-Piston Engines, of which the following is a specification.

My invention relates to improvements in rotating-piston engines; and the object of my 10 invention is to furnish an engine for the conversion of the direct and expansive force from steam, air, or other fluid into power by means of "compounding" and the utilization of a true cut-off operative at any part of the stroke 15 of the pistons, as in the highest type of steam-engine, from which it differs by its pistons and valve-gear being entirely rotative instead of reciprocating and its cylinders annular, surrounding the main shaft, thus utilizing the 20 persistence of inertia of the moving masses and avoiding the obstructive force of such masses in reciprocation. The pistons are directly and firmly attached to the main shaft of the engine, with only the interposing of a 25 cylindrical steam-chamber. The cylinders surround the pistons, and the valve-gear is carried in the steam-chamber, as hereinafter fully described.

For properly utilizing the expansive force 30 of the steam or other fluid and to obtain a perfect balance of the several parts I place the cylinders side by side, the rotation of their contained pistons being set in pairs upon planes crossing the axis of the main shaft at 35 right angles. The valve-gear, although direct and simple in its construction and operation, is designed to effect a perfect control of the valves and a wide range of cut-off without possibility of wiredrawing.

40 In the accompanying drawings, forming part of this specification, and in which similar reference characters indicate similar parts throughout the several views, Figure 1 is a longitudinal central sectional elevation through my engine, the main shaft, the valves and 45 valve-stems, and the yoke which secures the valve-stems in place being shown in elevation; Fig. 2, a section of Fig. 1 on line A B; Fig. 3, a section of Fig. 1 on line C D; Fig. 4, a sec- 50 tional view through the induction-valve and part of piston, showing port in latter; Fig. 5, a section of Fig. 1 on line E F; Fig. 6, a sec-

tion of Fig. 1 on line G H; Figs. 7, 8, and 9, enlarged sections of Fig. 1 on line K L, showing the actuating and actuated parts of the 55 valve-gear, the latter being shown in the different figures in different positions of rotation and gyration; Fig. 10, an isometrical view of the valve, valve-stem, and gearing; Fig. 11, an isometrical view of front end of 60 steam-passage connecting high and low pressure cylinders; Fig. 12, a side elevation of the low-pressure piston and its connected parts; Fig. 13, a front elevation of Fig. 12; Fig. 14, a section of Fig. 13 on line I J. 65

a b, Figs. 1 and 3, are cylinders, the former at the front and the latter at the rear of the engine. These cylinders, which are the high-pressure cylinders, receive steam directly from the steam-chest. 70

c d are pistons, the former in cylinder *a* and the latter in cylinder *b*.

e f, Figs. 1, 5, and 6, are the low-pressure cylinders, which are furnished, respectively, with pistons *g h*. The low-pressure cylinders 75 are placed inside—*i. e.*, between—the high-pressure cylinders and side by side, as shown in Fig. 1, the cylinder *e* receiving its steam from cylinder *a*, and the cylinder *f* from cylinder *b*. They both discharge their steam 80 through opening *i* into a condenser or into the open air. 70

j, Figs. 1 and 2, is an extension of the steam-chest, which is bolted to the head *k* of the cylinder *a*. This extension is connected with 85 the supply steam-pipe *l* and carries the valve-gear with its regulating apparatus. The steam-chest proper, *m*, surrounds the main shaft *n* of the engine and is interposed between the hubs *o* on this shaft and the inner 90 circumference of the cylinders *p' p² p³ p⁴*, to which the pistons *c d g h* are secured or of which they form part. The steam-chest is open from end to end, except for the radial arms *r*, Figs. 3, 5, and 6, which connect the 95 cylinder *p* (which is made up of the several cylinders *p' p² p³ p⁴*) with hub *o*. The outer periphery of the cylinder *p* rotates in contact with an abutment-cylinder *s*, Figs. 1, 3, 5, and 6, and, together with the abutment-cylinder, closes off at one point the cylinders *a b e f*, forming a stop against which the propelling fluid may react in order to move the pistons forward in their rotation. The abut- 100

- ment-cylinder has its axis of rotation parallel with that of the main shaft n , its bearings being parallel in axis with the main-shaft bearings and its shaft v being caused to rotate synchronously with the main shaft by means of gears $t u$, Fig. 1, carried upon these shafts, the gears being of equal diameter and pitch. To permit the pistons to pass the abutment-cylinder on completion of their stroke, which is equal to the outward and inward stroke of a reciprocating piston, this cylinder, which may be made in one piece, as shown in Fig. 1, or in separate pieces, one for each piston, is furnished with cut-away portions or ports w . In Figs. 1, 3, and 5 the high-pressure piston d is shown passing through its port w in the cylinder s . In order to reduce its weight, the abutment-cylinder is made hollow, as shown.
- 20 The gears $t u$, before referred to, drive the pistons and the abutment-cylinder at the same speed and insure each piston meeting and leaving its port in the abutment-cylinder at exactly the proper time. The gears are entirely inclosed by a shield x , through which the shafts $n v$ may pass, which is dust-proof, prevents danger in handling, and which makes perfect lubrication without radial spattering of oil easy to accomplish.
- 30 The oiling of all the moving parts, which are entirely inclosed, is effected not only by means of the usual "lubricator" (not shown) upon the entering steam-pipe l , but also by means of a passage 1 in the center of the main shaft n , which has its outer opening by removal of a plug or screw 2 at the outer center of the steam and valve chest j , a charge of oil or a continuous supply thereof being injected into opening 1 and being carried thereby, assisted by the steam or actuating fluid, to all the bearing parts through suitable channels or openings 3 3 3, &c., bored through the shaft, as indicated by dotted lines in Fig. 1.
- 40 Figs. 4, Figs. 1 and 10, is the valve for controlling admission of steam to high-pressure cylinder a ; 5, Fig. 1, a valve for controlling admission of steam to high-pressure cylinder b . These valves are precisely alike; but as the valve 4 controls the admission of steam to cylinder a , which is at front end of the engine, its stem 6 is shorter than the stem 7 of valve 5, which controls admission of steam to cylinder b , which is at rear end of engine.
- 50 The valves, valve-stems, and the gear-pieces 8, 9, 10, and 11, carried on the outer ends of the valve-stems, the purpose and operation of which will be presently described, are made by preference all in one piece.
- 60 12 is a yoke which is secured by bolts 13, Figs. 1 and 3, to the cylinder p' of the piston c .
- 14 represents bearings in yoke 12, through which the necks of the valve-stems 6 7 pass.
- 65 The bearings 14 are open at one end and are arc-shaped, being struck from center of shaft n , which passes through center of yoke. The

yoke engages a shoulder formed by an enlargement from the stem to the body of the valve itself and prevents the valves from being moved in or out. In order to engage or disengage the yoke with the stems, the bolts 13 are removed, permitting the yoke to be turned around on shaft n , a turning in one direction engaging the stems with the slots 14 and a turning in the other disengaging them.

Figs. 5 and 6 show the positions, relations, and action of the pistons with their steam-passages and valves. Each piston is mounted upon a section of the internal cylinder p , which forms the inner periphery of the separated annular cylinders $a b e f$, and are united one to the other by means of overlapping tight slip-joints 15, Fig. 1, and form together the continuous steam-chest m .

16 represents metallic packing-rings placed in seats in the periphery of cylinder p , which insure tight joints between this cylinder and its bearings in the partitions between the cylinders $a b e f$. These rings, running always in the same track and out of contact with the steam or other actuating fluid, are easily lubricated and cause but a very small amount of friction.

The pistons $c d g h$, the cylinder p , and the valves 4 5 are all carried into rotation with the shaft n .

The manner of the passage of the pistons through the ports of the abutment-cylinder s and the closing of the abutment-cylinder s against the internal cylinder p is made clear in Fig. 3. The packing to prevent passage of steam past sides of piston and ends of cylinder is also here shown. It has been found that the outer ends of the pistons require no packing to prevent passage of steam during rotation, except a series of capillary grooves 17, cut across them at right angles to the plane of motion. These grooves pick up enough moisture when passing the abutment-cylinder to effect a perfect packing without the piston end having a frictional contact with the cylinder. The stroke of each piston begins at the time of first contact between the abutment and internal cylinders, after its passage through the abutment-port, and when the piston reaches its seat against the periphery of its inclosing cylinder. The pistons are made with the contour shown in the drawings that they may fill as nearly as possible the abutment-port w , and thus reduce the "initial" clearance.

18 represents grooves formed in the seat of the abutment-cylinder, which permit steam to pass down and around this seat, except at the side contiguous to the exhaust-port i . This arrangement, while wasting no steam, because its action began while the piston was partly inclosed within the abutment-port, insures not only full useful expansion of the steam contained in that port through the stroke, but also the important requisite of an outer pressure in unison with the progress of expansion against the abutment-cylinder in

such direction as to secure its perfect contact with the internal cylinder p even though wear takes place in the bearings. It has been found that such close rolling contact, passing always toward the pressure side, and with the included moisture which is deposited from the exhaust side, not only insures a perfectly steam-tight joint, but produces no wear.

15 The peculiar relative positions of the pistons in the high and low pressure cylinders are caused by the necessity that in compounding the cylinders for continuation of expansive action from the high pressure to the low pressure. 20 sure the high-pressure piston goes out of action at the end of its stroke at the moment contact between the cylinders p is broken to permit it to pass through its port in the cylinder s . Therefore the low-pressure piston is so placed 25 that at this same moment it shall have the contact with its internal and abutment cylinders made perfect and also its own complete seating for the beginning of a new stroke. The only outlet from the high to the low pressure cylinder is through a passage 19, formed in the advancing face of the high-pressure piston, which leads direct to a similar passage 20 in the back of the low-pressure piston, and as 30 the high and low pressure cylinders lie in different planes and are otherwise completely closed to each other it will be seen that no steam can pass from the high to the low pressure cylinder for a new stroke until the high-pressure cylinder is opened to the advancing 35 of its piston primarily by the opening of its abutment-port, from which time all the contained steam before that piston can pass through the passage 19 into the low-pressure cylinder behind its piston up to the end of 40 the stroke of the high-pressure piston; but it is evident that the low-pressure piston must have attained its seat after passing the abutment s and the abutment s and internal cylinder p be again in perfect peripheral contact before this can be permitted. In this 45 manner the abutment and its port belonging to the high-pressure cylinder, combined with the relative positions of the two pistons and the abutment and port of the low-pressure 50 cylinder, effect a valve action which always admits the partly-expanded steam of the high-pressure cylinder, beginning only at the end of its piston-stroke and just as the low-pressure piston is safely ready for action, 55 while the actuating part of the high-pressure cylinder is always shut off from the low-pressure cylinder and the exhausting portion of the low-pressure cylinder is always shut off from communication with the high-pressure 60 cylinder. The expansion begun in the high-pressure cylinder is thus completed in the low-pressure cylinder without the disadvantages accompanying an intervening "receiver" and a second series of valves with 65 their attendant gear.

As the engine is to be carefully balanced in all its running parts and as the adjacent

high and low pressure pistons cannot be balanced against each other—that is, placed upon opposing radii—I have found it advantageous to construct the engine with two sets of high and two sets of low pressure pistons, each working in its own cylinder, as shown, which sets of pistons I oppose in radial position. It will be understood that the cylinders may be arranged, as shown, with the high pressure outside and the low pressure inside, or that this arrangement may be reversed, so that the low pressure will be outside and the high inside.

The induction-valves 45, which are shown in position in Fig. 1, in section in Fig. 4, and in perspective in Fig. 10, and the induction-port 21 in the back of the high-pressure pistons (shown in section in Fig. 4) are arranged 85 for action at the bases of the high-pressure pistons only, with which they rotate about the main axis of the engine, and they have in addition to this motion of rotation a rotation upon their own axes caused by the gearing carried on the outer ends of their valve-stems and the mating gear carried upon the bearing in center of the outside steam-chamber j , which motion of rotation admits steam to the ports 21, formed in the rear faces of 90 the high-pressure pistons. The induction-valves 45 are cylindrical and have cut through them radial ports or slots 22 of such number as may be most convenient—in the present construction three, all meeting in the axis of 100 the valve—and of such dimensions as shall have when admitting steam an ample opening from the steam-chest to the piston-port. As the body of the valve containing these slots is entirely open to the steam-chest m , 105 with the exception only of the bearing upon the seat at the piston-port, it follows that its partial rotation upon its own axis—one-sixth of a full rotation with the present construction—will close or open the port to the full 110 pressure of the steam-chest. With the port 21 open one of the openings 22 in the valve will be continuous with it and steam will be freely admitted through the other ports 22. A one-sixth rotation of the valve will close 115 port 21, as shown in Fig. 4, and the flow of steam to this port will be stopped. As the valve rotates upon its axis always in one direction, a complete rotation of it takes place once in three rotations or strokes of the piston—that is, three openings and three closings of the piston-port are effected in that time. The opening of the port, as has been seen in describing the piston-stroke, must always be effected at one definite part of that stroke or 125 rotation—i. e., just as the piston is in position to begin a new stroke—while the closing may take place at any portion of the stroke, provided it be effected before its completion, and thus prevent full pressure of steam from 130 entering while the piston is passing the abutment-port and its two sides are open to each other.

The valve-gearing is all within the outer

steam-chest *j* and is designed to accomplish the opening and closing of the valves for each stroke of the high-pressure pistons. It consists of an actuating part resting upon the bearing, into which the outside end of the main shaft *n* fits, and of an actuated part carried by the ends of the valve-stems. The actuating part has two separate divisions 23 24, Fig. 1, the first so placed that it may be rotated to the radial position needed to effect the desired point of cut-off and the second in a firmly-fixed position.

8, 9, 10, and 11, Figs. 1 and 10, are pieces upon the end of the valve-stem forming the actuated part of the gearing. 8 and 9 operate in connection and plane with the movable part 23 of the actuator and 10 and 11 in connection and plane with the stationary part 24 of the actuator.

20 Upon a bearing formed for the purpose about the outer end of the main shaft *n* are placed the two rings or cylindrical pieces 23 24, each having in protrusion from its surface a cam-shaped tooth 26, Figs. 2, 7, 8, and 9, at 25 the side of which is a depression 27 in the ring upon a different plane. The ring 24 is firmly fixed upon the bearing at its inner end and actuates the valve-opening gear and forms a guard which keeps the other ring 23 in position. The ring 23 has rotation upon its bearing, controlled from the outside of the engine by suitable means, in the present case a worm-gear 28, with its stem 29 passing upward and outward through a gland 30 in the chest *j*. The 30 actuated gear upon the valve-stem for each division—that is, one gyrating in plane with the actuator which opens and the other with that which closes the valve—has two parts, one in plane with and to fit over the cam-shaped 35 tooth 26, which is its actuator, and the other in plane with and to fit into the depression 27 at the side of the actuating-tooth. As there are six partial rotations to complete one full rotation of the valve—three for opening 40 and three for closing—each section of the actuating-gear is formed with three double radial parts in plane with the double parts of the opening-actuator and three with those of the closing-actuator. These are formed for 45

50 each division upon the stem with three arc depressions 31, rounded at the ends, in plane with and to fit over the tooth 26 of the actuator and three rounded spurs 32 of a little longer radius in plane with and to fit into the 55 depression 27 at center side of the tooth 26. The arc depressions 31, which in their turn fit over the tooth 26, and the accompanying spurs for the opening-actuator alternate in radial position upon the valve-stem with 60 those which are to fit upon the closing-actuator. Consequently first one division 10 11 is used to open the valve, and on further gyration of the valve-stems the other division 8 9 reaches its actuator and closes it. Between 65 these actions the spur which has just completed the partial rotation of the valve by passing out of its depression throws the spur

of the other division down upon the continuous peripheral surface 33, upon which it runs until it is ready for entrance into its own depression, while it itself passes onto and runs upon its own continuous peripheral surface. Thus a locking of the revolution of the valve about its own axis is effected until the forward spur can pass again into its fitting depression. 70 It will be seen that the beginning of each one-sixth rotation of the valve is effected by a smooth and gently-increasing motion through the spur which forms one outward end of the depression into which the actuating-tooth fits, 75 the one which is behind the tooth in direction of motion riding easily and without jar upon the reverse arc of that side of the tooth, and thus turning the valve until the depression and tooth fit center to center, while the 80 spur upon the plane by their side fits into its corresponding depression and on passing out completes the movement with the same degree of smoothness in action. The valve-stems being held in the bearings in the yoke 12 90 close to the seat of this action, it is effected smoothly and without any straining of the parts.

Figs. 7, 8, and 9 show the operation of the valve, as described.

95 No valve is needed to control the passage of steam between the high and low pressure cylinders except such as has been described, effected through action of the abutment-cylinder and its piston-ports. This passage is 100 freely through the port 19 at the forward face of the high-pressure piston *c*, (it being understood that the operation and arrangement of the ports for both sets of high and low pressure cylinders are identical,) as that piston and its cylinder are on a different plane from the low-pressure piston *g*, through the back of which the induction-port 20 for that cylinder is placed. A lateral passage 34 is placed beneath the base of the pistons within the internal cylinder *p* and in line with the passage between two of its supporting-arms. As this internal cylinder is made in sections, one to each piston, and as the required passage for the partly-expanded steam 105 should not be in any way open to the initial steam in the central steam-chest *m*, this passage has a peculiar formation and inclosing, which will be made clear from Figs. 1, 3, 5, 6, 12, 13, and 14. It is formed directly in 110 and cast with the section of the internal cylinder *p* supporting the low-pressure piston. It has about it an inclosed space 35, empty or filled with non-conducting material and guarded on its sides next the steam-chest by 115 outer walls supported against the internal-cylinder arms. From this section of the cylinder *p* it passes out through its end, as at 36, Figs. 12, 13, 14, and fits into similarly-guarded outer walls cast in section *p'* of the 120 internal cylinder, where it fits tightly against the exhaust-port 19 of the high-pressure piston and is prevented from springing out of contact with that port by the protuberance 125

37, formed upon its end and which fits into a socket in the section p' . In this manner a free continuous passage is provided leading from the exhausting side of the high-pressure piston to the actuating side of the low-pressure piston, which passage is guarded from a transfer of the heat of the initial steam by the insulating-spaces surrounding it and the outer wall surrounding those spaces. The 5 space before the exhaust side of the low-pressure pistons is always open to the free exhaust-ports i' , which ports join together in the exhaust-port i . The actuating sides of these pistons are entirely closed off from the 10 exhaust-ports of their cylinders through the whole stroke by means of the abutment-cylinder s and because of the relative positions of the high and low pressure pistons and the valve action of the abutment during the 15 passage of the pistons through the abutment-ports at any time from the high-pressure cylinder to the low-pressure exhaust-ports.

Radiation and convection of heat from the engine and its parts where it could cause loss 20 of energy are carefully guarded against by the provision of insulating-spaces 38, Fig. 1, filled with non-conducting material where necessary.

The high-pressure cylinders placed at either 25 end of the engine are connected to its main casing in a peculiar manner, with the intervening space 39 and by flanges 40 to secure insulation for heat between the high and low pressure cylinders and to permit a ready assembly 30 of the respective parts. The internal cylinder p , which supports the pistons and the outer wall of the steam-chest, is made and put together in sections $p' p^2 p^3 p^4$, with the same purpose and to facilitate the arrangement 35 and placing of the packing-rings 16. These packing-rings are circumferential and sprung into position upon the internal and the abutment cylinders at every division between the annular cylinders, while at the 40 high-pressure and low-pressure divisions at either end there are two for each dividing-space. For the outer ends of the high-pressure cylinders the packings are different, having their pressure against a plane at right angles 45 to the axis except at the actuating end of the main shaft and when needed for reverse motion at the corresponding end of the abutment-cylinder shaft. The main bearings for the shafts are closed at the outer end, which obviates necessity for glands and packing-boxes. 50 At the actuating end of the engine these shafts have metallic rings 42 about them in pressure with the shafts and their bearings in the head of the case, which prevent a passage 55 of steam at these bearings.

The gear-case is tightly closed and has at its upper portion a reservoir 41, with a tight plug 43 to close the entrance for holding oil, which is distributed therefrom to the main 60 bearings, preferably through connecting-tubes 44.

Having thus described my invention, I

claim as new and desire to secure by Letters Patent—

1. The combination in a rotating-piston engine of two or more sets of pistons, one set balanced against another set, rotating about a common axis, separated annular cylinders within which said pistons rotate, a cylindrical internal fluid-chamber, surrounding the main axis of the engine, upon which said pistons are secured and which is open from end to end, a central shaft to which said internal chamber is secured, cylindrical valves rotating within said chamber and, with exception 70 of their seats surrounded by the fluid within said chamber, by means of which the flow of the actuating fluid to the piston-cylinders is controlled, means for rotating said valves, and a rotating abutment-cylinder preventing 75 the passage of the actuating fluid from one side to the other of said pistons.

2. In combination, a valve having a motion of rotation about a center and a motion of rotation upon its own axis, two sets of gearing, 80 each set consisting of two parts, upon the stem of said valve, a cylindrical stationary bearing operating in connection with an adjustable bearing and parts of each set of gearing on said valve-stem to firmly hold the 85 valve from rotation on its own axis between the times necessary for the opening and closing of the ports while rotating about the common axis, an adjustable cylindrical bearing furnished with mating gearing operating in 90 connection with one of the sets of gearing on said stem to rotate said stem on its own axis for closing the cut-off, and means whereby said adjustable bearing may be rotated in order to regulate the cut-off. 95

3. The combination with the cylindrical steam-chamber and the gyrating valves and valve-stems carried thereby, of a yoke adapted to be bolted to the end of the steam-chamber and furnished with slotted arms adapted 100 to surround said valve-stems as and for the purposes set forth.

4. The described means for securing the induction-valves in place and for forming a bearing close to their actuators, consisting of 105 a yoke furnished with arms having arc-shaped slots adapted to pass over the valve-stems, said yoke being adapted to rest upon a central bearing and to be engaged or disengaged with the stems by a partial revolution on its 110 bearing, and being adapted to be held in place by bolts substantially as described.

5. In a compound rotating-piston engine, in combination, two or more sets of high and low pressure cylinders placed side by side and 115 upon a common axis, an open cylindrical steam-chest passing centrally about the axis upon which said cylinders are formed, a shaft axially central of said steam-chest and secured thereto, pistons carried peripherally by said 120 steam-chest, a cylindrical abutment engaging the cylinder forming said steam-chest peripherally, valves controlling the admission and cut-off of steam to the high-pressure cylin- 125 130

ders, and means for admitting the steam to the low-pressure cylinder directly from the high-pressure cylinder.

6. The combination in a rotating-piston engine of two or more annular cylinders placed side by side upon a common axis, a steam-chest without said cylinders, a hub with arms carrying a hollow annular internal cylinder passing centrally through said cylinders forming when in place a continuation of said steam-chest and carrying an insulated passage for conducting the actuating fluid from the high to the low pressure cylinder, said hub, arms, and cylinder forming together a removable cylinder, said removable cylinder, pistons firmly fixed to said internal cylinder, a shaft to which said hub is secured and which forms its axis, an external rotating abutment, furnished with ports for the passage of said pistons, engaging said internal cylinder tangentially and longitudinally, means for rotating said abutment and internal cylinders synchronously, and means for admitting the actuating fluid to and for exhausting it from said cylinders.

7. In a rotating-piston engine, in combination, a high and a low pressure cylinder placed side by side upon a common axis, an internal cylinder passing centrally about the axis upon which said cylinders are formed, pistons carried by said internal cylinder, means for admitting the actuating fluid to the high-pressure cylinder, an abutment-cylinder engaging said internal cylinder peripherally and furnished with ports to permit the passage of the pistons carried by said internal cylinder, means for rotating said internal and abutment cylinders at the same speed, and means for transferring the actuating fluid from the high to the low pressure cylinder during the passage of the high-pressure piston through its port in the abutment-cylinder and afterward throughout the stroke.

8. A compound rotating-piston engine consisting of two or more annular cylinders placed about the same axis upon different planes, each cylinder containing a rotating piston, the high-pressure piston having an inlet-port upon its rear face and an outlet-port through which the actuating fluid may pass, in exhaust, upon its advancing face, said latter opening being connected by an insulated passage with an opening on the rear face of the low-pressure piston, and a rotating abutment

cylinder furnished with ports for the passage 55 of said pistons.

9. The described means for conducting the actuating fluid from the high to the low pressure cylinder consisting of a hollow protrusion formed upon one section of the internal 60 hollow cylinder and a seat formed within the contiguous section said seat being adapted to receive said protrusion, and means for holding said protrusion firmly against its seat.

10. In combination, a valve having a motion of gyration around a center and a motion of rotation upon its own axis, a gearing upon the stem of said valve consisting of two parts each of which is subdivided into two parts, one subdivision of each part forming sockets 70 or interspaces adapted to be engaged by a tooth upon an actuator having its bearing and axis upon the center of gyration of the valve-stem, and the other subdivision having spaces equal in number to the sockets on the first 75 subdivision their centers being upon the same radius with them, adapted to engage a depression having its center upon the same radius but upon a different plane from said tooth engaged by the other subdivision, the 80 actuating and actuated parts alternating with each other in position and action for the opening and closing of the valve.

11. In combination, a valve having a motion of gyration around a center and a motion 85 of rotation upon its own axis, a gearing upon the stem of said valve consisting of two parts each of which is subdivided into two parts, one subdivision of each part forming sockets or interspaces adapted to be engaged by a 90 tooth upon an actuator having its bearing and axis upon the center of gyration of the valve-stem, and the other subdivision having spurs equal in number to the sockets on the first subdivision, their centers being upon the 95 same radius with them, adapted to engage a depression having its center upon the same radius with but upon a different plane from said tooth engaged by the other subdivision, and said actuator, the actuating and actuated 100 parts alternating with each other in position and action for the opening and closing of the valve, and the actuator for the closing of the valve being adjustable.

JOSIAH DOW.
